UNITED STATES PATENT OFFICE.

ROBERT JACOB GÜLCHER, OF CHARLOTTENBURG, GERMANY.

MOLD FOR FRAMING ELECTRODES.

SPECIFICATION forming part of Letters Patent No. 674,407, dated May 21, 1901.

Application filed June 28, 1900. Serial No. 21,992. (No model.)

To all whom it may concern:

Be it known that I, ROBERT JACOB GÜLCHER, engineer, a subject of the King of Prussia, German Emperor, residing at the city of 5 Charlottenburg, near Berlin, in the Kingdom of Prussia, German Empire, have invented certain new and useful Improvements in Molds for Framing Electrodes of Thin Lead Strips, of which the following is a full, clear, 10 and exact description.

The present invention relates to a process for providing electrodes made of thin strips of lead placed alongside or over one another, with lead rims or frames cast around them.

15 In the American Patent Specifications Nos. 612,649 and 624,513 electrodes are described which are made of a single strip of lead having a rim cast around it in a mold. In this arrangement the lead strips are placed in the 20 mold and have to be held in position during the casting by means of projecting ribs or like arrangements. The accurate adjustment of the single strips in the mold requires much time and specially-experienced workmen, so 25 that this method of construction is very complicated and costly.

The holding of the separate strips firm by means of projecting ribs or the like necessitates the use of proportionately thick lead strips, as thin strips arranged 30 parallel at certain distances apart would become too much distorted by the means necessary for holding them fast. To obviate the inconveniences and defects according to the present invention, special core frames are 35 employed, in which the thin strips or plates of lead are superposed in layers before the casting and separated from one another by rather shorter strips of paper or the like.

The strips or plates can be placed in layers in 40 the core-frames by hand or by mechanism. The core-frame, filled with the strips of lead and paper, is closed by means of a suitable lid. Only the ends of the lead plates project 45 slightly over the sides of the core-frame,

whereas the strips of paper or the like are cut even with the sides. According to the size of the electrode to be made a number of core-frames are arranged as cores at a suitable distance apart in a casting-mold, as is done with 50 cores in the ordinary process of core-casting. These core-frames have then lead poured around them for the frame. The molten lead

consequently penetrates into the spaces between the lead plates projecting from the frames, and consequently incloses the ends 55 thereof on all sides and partially fuses them, so that all the lead plates are intimately connected with the frame cast around them. During the aforesaid casting around the lead plates the strips of paper prevent the further penetration of the molten lead and at 60 the same time assure the requisite distance apart of the lead plates.

For the better comprehension of the invention the new casting process is illustrated in 65 the accompanying drawings, in which—

Figure 1 shows a core-frame filled. Fig. 2 is an enlarged section on the line A B of Fig. 1. Fig. 3 is a plan view of Fig. 1. Fig. 4 shows in elevation an electrode constructed by the 70 use of twelve core-frames. Fig. 5 is a section on the line C D of Fig. 4. Fig. 6 is a view of one-half of the mold with six inserted core-frames, while the other six core-frames are 75 omitted to illustrate the casting-plate itself. Fig. 7 is a vertical section through the mold on the line E F, Fig. 6.

The lead strips *a* are superposed in layers alternately, with the strips *b* of easily destructible material (preferably paper) in the 80 core-frame. The core-frame consists of the parts *c* and *d*, of which *c* forms the sides and *d* the bottom and top. The parts *c* and *d* are formed of suitable metal—for instance, steel or iron—and fit easily and interchangeably into one another, the lugs or pins *e* of the bottom and top engaging in slots of the sides. The pins *e* therefore serve, on the one hand, for joining the core-frames together, and, on the other hand, are likewise intended 90 to keep the core-frames fixed in their appointed position in the casting-mold, as they engage in corresponding recesses *i* in the said mold.

The mold has a mouth *k* and channels *l* for 95 introducing the molten lead.

For constructing the electrode illustrated in Figs. 4 and 5 twelve core-frames are inserted side by side at suitable distances apart in a casting-mold comprising two casting-plates *A* and *B*, as clearly shown in Figs. 6 and 7. On casting around the core-frames the frame *g*, as shown in the drawings, will be formed, which is cut off even with the edges

of the core-frames inserted therein, as the strips of paper or the like are of the exact length of the sides. As soon as the frame has set the mold is opened and the core-
5 frames taken out, so that only the lead plates surrounded by the lead frame *g* remain behind. By drawing out the parts *d* the empty spaces *h* between the plates *a* and the frame *g* are formed. These intermediate spaces *h*
10 present the advantage of allowing the lead plates room for expansion during the formation or charging.

In order to remove the strips of paper still remaining between the lead plates, the electrode is immersed in a suitable corrosive or solvent medium, such as sulfuric acid or the like. If the electrode is then allowed to lie exposed to the air, the paper will be completely destroyed after some time. The
15 process of destruction will be accelerated by drying the electrode in a warm place.

By the process described almost any desired increase of the surfaces of the electrode can be produced, as it is only necessary to
20 suitably select the thickness of the strips of
25

lead and paper or the like. It is a further valuable advantage of this new process that electrodes with differently-sized—*i. e.*, differently-divided—surfaces can be formed by means of the same casting-mold.

30

I claim—

The combination of two casting-plates having recesses *i*, said plates placed on each other with a number of core-frames located between them, which frames consist of side parts *c* and intermediate end parts *d*, one end part *d* forming the bottom and the other the top of the frame, said sides *c* having the shoulders or projections *e* engaging the openings *i* of the casting-plates and thus holding the core-frames in their correct position between the casting-plates, substantially as described.

35 In witness whereof I have hereunto set my hand in presence of two witnesses.

40 ROBERT JACOB GÜLCHE.
